UNITED STATES PATENT OFFICE.

JOHN C. SHAFFER AND LYNN S. MANKIN, OF TULSA, OKLAHOMA, ASSIGNORS TO
TULSA VALVE COMPANY, OF TULSA, OKLAHOMA.

WATER GAUGE FOR BOILERS.

Application filed October 29, 1926. Serial No. 144,993.

Our invention relates to improvements in water gauges.

In accordance with our invention, a water gauge is provided which is adapted for use upon high pressure steam boilers, while not necessarily restricted to this use. The water gauge is made of three major parts. The valve element or housing is mounted to reciprocate upon the stem of the body portion. 10 This valve element or housing has a downwardly directed port for the discharge of the steam or water. The valve element or housing is readily separable from the body portion. The valve element or housing carries a valve seat, formed of relatively soft non-corrosive material, for co-action with the outlet end of the stem of the body portion and the contacting surfaces are so constructed that a tight joint is effected between the same, when in contact and the tendency of the seating element to travel or become disturbed, is eliminated. The device further embodies a handle having a part to engage with an outer cam face formed upon the valve element or housing, said handle also having additional means for opening and closing the valve element or seat.

Other objects and advantages of the invention will be apparent during the course of the following description.

In the accompanying drawings, forming a part of this specification, and in which like numerals are employed to designate like parts throughout the same,

Figure 1 is a side elevation of a water gauge embodying our invention,

Figure 2 is a plan view of the same,

Figure 3 is a central vertical longitudinal section through the body portion and valve element or housing, parts being broken away, and,

Figure 4 is a perspective view of the body portion and valve element or housing, showing the same separated, for the purpose of illustration.

In the drawings, wherein for the purpose of illustration, is shown a preferred embodiment of our invention, the numeral 5 designates a stationary tubular body portion, which is preferably flat and provided with a longitudinal bore 6. The body portion is horizontally arranged and is provided at its forward end with a tubular screw-threaded stem 7, for engagement

within an opening formed in a boiler shell 8. The body portion is provided with a polygonal portion 9, for convenient engagement with a wrench or like tool. The flat body portion 5 is provided at its rear end with a tubular stem 10, through which the bore 6 passes. This tubular stem is preferably circular in cross section. The tubular stem is provided at its rear or free end with a head or nozzle 11, having a contracted port 12. Surrounding this contracted port, are a pair of spaced concentric contact rings 13 and 14, formed upon the head or nozzle 11, as shown.

The tubular stem 10 is preferably horizontally arranged, and projects into a cylindrical opening or bore 15 of a valve element or housing 16, which is preferably flat, as shown. The opening 15 is cylindrical and the valve element or housing is held against turning movement upon the body portion 5, by means of a forwardly projecting extension 17, having a flat horizontal shoulder 18, arranged to slidably engage beneath a horizontal shoulder 19, formed upon the body portion. In the normal operation of the device, in testing the water level, these shoulders 18 and 19 remain in sliding contact. The valve element or housing 16 is provided with a downwardly directed vertical outlet opening or port 20, as shown. This valve element or housing is also provided in its rear end with a recess 21, leading into the opening 20, and this recess receives a seating element 22, formed of a relatively soft non-corrosive material, such as lead, babbitt, zinc, copper, or compositions of asbestos and graphite, or the like. This seating element has annular grooves formed therein, by the action of the contact rings 13 and 14. These contact rings, together with the sliding or reciprocating movement of the valve element or housing, serves to eliminate the tendency that the material of the seating element 22 might have to travel or become disturbed, thereby assuring a tight joint. As the seating element 22 wears down, a new seating element may be replaced, as is obvious.

The numeral 23 designates a weighted handle, the forward end of which is forked to provide a pair of spaced arms 24, to be arranged upon opposite sides of the valve element or housing 16 and the body portion 5. These arms 24 are provided at their

forward ends with transverse heads 25, extending laterally above and below the arms 24, as shown. The upper ends of these heads are apertured for receiving pivot elements or trunnions 26, carried by the body portion 5. The lower ends of the heads 25 project downwardly between stop elements, pins or trunnions 27 and 28, carried by the valve element or housing 16, or extension 17 thereof. The forward pins 27 engage forward cam faces 29 and the rear pins or elements 28 are adapted to engage rear cam faces 30. The distance between the pins 28 and 27 is greater than the width of the lower ends of the heads 25, thereby permitting of slight play between the parts, for a purpose to be described.

The handle 23 is provided adjacent to the bases of the arms 24 with a tapered nose or cam 31, arranged to engage with a curved or cam face 32, formed upon the rear end of the valve element or housing 16.

In operation, when the weighted handle is released or moved downwardly, the cam faces 29 contact with the pins 27, thereby shifting the valve element or housing 16 forwardly, so that the head 11 contacts with the seating element 22. The cam face 31 also contacts with the cam face 32, affording a powerful compound action in holding the head 11 upon the seating element 22. When the valve element or housing 16 is to be shifted outwardly, for testing the water level, the handle 23 is moved upwardly. The cam face 31 turns upon its pivots 26, which is eccentric to the arc of the cam face 32, and the cam face 31 moves sufficiently out of the path of travel of the cam face 32 before cam faces 30 engage pins 28, for effecting the outward movement of the valve element or housing. The further upward movement of the handle 23 increases the distance between cam faces 32, and 31, and the further outward movement of the valve element or housing 16 is accordingly permitted. When the valve element or housing 16 is in the inner or closed position the contact rings 13 and 14 become imbedded within annular grooves formed in the relatively soft seating element 22, and this prevents any tendency of the seating element to spread or become distorted. The opening 20 causes the steam to escape in a downwardly direction. The valve element or housing may be readily separated from the body portion, when desired, for replacing the seating element 22, and this may be done when the boiler is under steam pressure. Only a small amount of the steam will escape through the contracted port 12 and the operator stands at the side of this port out of the way of the steam.

It is to be understood that the form of our invention, herewith shown and described, is 65 to be taken as a preferred example of the

same, and that various changes in the shape, size and arrangement of parts may be resorted to without departing from the spirit of our invention or the scope of the subjoined claims.

Having thus described our invention, we claim:—

1. In a water gauge, a tubular body portion for connection with a boiler, said tubular body portion having a tubular stem provided with an outlet opening at its free end, a reciprocatory housing mounted to slide upon the tubular stem and having a laterally extending outlet opening, said housing being provided at its outer end with a cam face and having a seating part to engage with the outlet end of the tubular stem, a handle provided at its forward end with a pair of spaced arms and having a cam face between the arms for contact with the cam face of the housing, said arms being provided at their forward ends with transverse heads extending above and below the same, means for pivotally connecting the upper ends of the transverse heads with the body portion, and shifting elements carried by the housing and arranged forwardly and rearwardly of the lower ends of the transverse heads to contact therewith.

2. In a water gauge, a tubular body portion for connection with a boiler and having an outlet, a reciprocatory housing mounted upon the tubular body portion and having a part to cover said outlet and being provided with an outlet opening, said housing having an outer cam face, a handle, provided at its forward end with a pair of spaced arms which are pivotally mounted upon the tubular body portion and are provided with lateral extensions said handle having a part to engage said cam face, and shifting elements carried by the housing and arranged upon the forward and rear sides of said lateral extensions.

3. In a water gauge, a tubular body portion for connection with a boiler and having an outlet, a reciprocatory housing mounted upon the tubular body portion and having a part to cover said outlet and being provided with an outlet opening, said housing being provided at its rear end with a cam face, a handle provided at its forward end with a pair of spaced arms which are pivotally mounted upon the tubular body portion at points eccentric with relation to the cam face of the housing, said handle having a part to engage with said cam face, and shifting elements carried by said housing, said arms having lateral extensions operating between said shifting elements with the distance between the shifting elements being greater than the width of the lateral extensions to provide for lost motion.

4. In a water gauge, a tubular body for connection with a boiler and having an out-

let, a housing mounted to reciprocate upon the tubular body and having an outlet and a part to cover the outlet of the tubular body, said housing having an outer contact face, 5 and a lever pivotally connected with the tubular body and having a face to engage the outer contact face of the housing, said faces being adapted to have wedging action, and means connecting said lever with the 10 housing so that the housing may be positively shifted to the open position by the movement of the lever in one direction.

5. In a water gauge, a tubular body for connection with a boiler and having an outlet, a reciprocatory valve member mounted upon the tubular body and having a part to cover said outlet, said valve member having an outer contact face, a lever pivotally connected with the tubular body and having a 20 contact face adapted to have engagement with the first named contact face, and a lost motion connection between the lever and the valve member whereby the valve member may be positively shifted to the outer position 25 by the movement of the lever in one direction after the outer contact face of the reciprocatory valve member has been released by the contact face of the lever.

6. In a water gauge, a tubular body having a flat shoulder and carrying a tubular stem provided with an outlet, a housing

mounted to reciprocate upon the tubular stem and having a part to cover the outlet and provided with a substantially flat extension arranged in lapping relation with 35 the shoulder, a lever pivotally connected with the tubular body portion and provided with a lateral extension, and connecting means between said lateral extension of the lever and the housing whereby the housing 40 may be positively shifted in opposite directions by the movement of the lever.

7. In a water gauge, a tubular body portion for connection with a boiler and having a tubular stem provided with an outlet, said 45 tubular body portion having a shoulder, a reciprocatory housing mounted upon the tubular stem and provided with a laterally directed outlet and having a part to cover the outlet to the tubular stem, said housing 50 having an extension arranged in overlapping relation with said shoulder, a lever pivotally connected with the tubular body portion and having a crank, and shifting elements secured to the housing and arranged 55 upon opposite sides of the crank to engage therewith.

In testimony whereof we affix our signatures.

JOHN C. SHAFFER.
LYNN S. MANKIN.
